F. H. BLAISDELL,
ADJUSTABLE SHADE ROLLER BRACKET,
APPLICATION FILED AUG. 2, 1919.

1,332,285.

Patented Mar. 2, 1920.

INVENTOR

Frank H. Blaisdell

BY Geo. D. Phillips

his ATTORNEY

UNITED STATES PATENT OFFICE.

FRANK H. BLAISDELL, OF BRIDGEPORT, CONNECTICUT.

ADJUSTABLE SHADE-ROLLER BRACKET.

1,332,285.

Specification of Letters Patent.

Patented Mar. 2, 1920.

Application filed August 7, 1919. Serial No. 315,783.

To all whom it may concern:

Be it known that I, FRANK H. BLAISDELL, citizen of the United States, residing at Bridgeport, in the county of Fairfield and 5 State of Connecticut, have invented certain new and useful Improvements in Adjustable Shade-Roller Brackets; and I do hereby declare the following to be a full, clear, and exact description of the invention, such as 10 will enable others skilled in the art to which it appertains to make and use the same.

My invention relates to new and useful improvements in shade roller brackets of the adjustable type. The object of my invention is to provide a bracket having all 15 the necessary requirements of strength, durability and cheapness, and it consists in making each member comprising the bracket of sheet metal, and each member made of a 20 single piece of metal formed into the required shape by proper tools.

Referring to the drawings wherein the same figures and letters of reference indicate like parts throughout the several views:

25 Figure 1 represents an elevation of an assembled bracket and broken view of a shade roller supported thereon;

Fig. 2 is an end elevation of the bracket looking in the direction of arrow *a*, Fig. 1, 30 with the roller removed showing the roller supported in locked position;

Fig. 3 is an end elevation of the bracket and broken view of the roller support in its neutral unlocked position;

35 Fig. 4 is a plan view of the roller support and its sliding carrier showing the roller support in a neutral position;

Fig. 5 is a plan view of the roller support and its sliding carrier showing the roller 40 support in its lowest locking position;

Fig. 6 is a side elevation of the sliding carrier and broken view of the roller support showing the latter in a neutral position;

45 Fig. 7 is an end elevation of the sliding carrier and roller support;

Fig. 8 is a side elevation of the sliding carrier and broken view of the roller support showing the latter in its lowest position;

50 Fig. 9 is a detail plan view of the blank from which the base plate is formed;

Fig. 10 is a detail elevation of the sliding carrier;

55 Fig. 11 is a detail plan view of the blank from which the carrier is formed;

Fig. 12 is a detail end elevation of the roller support;

Fig. 13 is a detail side elevation of the roller support; and

Fig. 14 is a detail plan view of the blank from which the roller support is formed.

The bracket consists of three sheet metal members comprising the channel base plate 1, carrier 2 and roller support 3 assembled 65 in working order as shown in Fig. 1. Each member, as before mentioned, is made of a single piece of sheet metal formed into proper workable shape to give the best results as to strength, lightness, cheapness and 70 durability.

The upper edges of the channel base plate are bent inward at right angles to the sides to form the lips 4—5. The upper edges of the inclined sides 6 of the carrier 2 are bent 75 outward, Fig. 10, to form the lips 7 so that the carrier will have a free longitudinal movement between the floor of the channel base and the under surface of the lips 4—5 of said base and be confined therein, as 80 clearly shown in Figs. 1, 2 and 3.

The roller support blank shown in Fig. 14 has the right angle projection *b* of which the angular head 8, Figs. 7 and 12, is formed. This head has the inclined sides 9 adapted 85 to have a sliding fit within the carrier as shown in Fig. 7, and a sliding movement at right angles to the movement of the carrier.

The lower lip of the channel base is provided with the notches 10 adapted to receive 90 the bridge portion *c* of the roller support to lock said support firmly to the channel base. To adjust the roller support with respect to the position of the roller 11, the support is simply raised out of contact with the notches 95 and moved longitudinally with its carrier 2 in either direction until the proper position is located.

As before mentioned, the several members of the bracket are made of sheet metal 100 formed into the proper shape by automatically operating tools. No hand labor is required in fitting and adjusting the members, as they can readily be assembled by the purchaser. There are no adjusting screws or 105 extra parts required in connection with the three members, viz.: the channel base, sliding carrier and roller support.

Having thus described my invention, what I claim as new is:—

1. An adjustable shade roller bracket of the character described comprising a one

piece sheet metal channel base plate having inwardly turned lips, one of said lips provided with a series of notches, a one piece sheet metal carrier having a longitudinal movement on the channel base and under said lips, and a one piece sheet metal roller support having a head slidably mounted in the carrier and having a movement therein independent of and at right angles to the movement of the carrier, said roller support adapted to engage any one of the notches of the channel base plate and within the limit of its travel along said channel base plate.

2. An adjustable shade roller bracket comprising a one piece sheet metal channel base plate having inwardly turned lips, one of said lips provided with a series of notches, a one piece sheet metal carrier having inwardly inclined sides and outwardly turned lips, the latter engageable with the base plate lips, said carrier having a longitudinal movement on the channel base plate and under its lips, and a one piece sheet metal roller support having a head whose sides register with the sides of the carrier and having a free sliding movement therein in-

dependent of and at right angles to the movement of said carrier and between the sides of the latter, said roller support adapted to be located in any one of the notches 36 of the channel base plate.

3. In a shade roller bracket, a base having a guide way formed with a series of vertical notches, a carrier horizontally slidable in the guide-way, and a roller support borne by 35 and vertically slidable with respect to and independent of the carrier and formed with a part receivable in one of said notches.

4. In a shade roller bracket, a base having a guide way formed with a series of vertical 40 notches, a carrier horizontally slidable in the guide-way, and having a vertical substantially dove-tailed shaped guideway, and a roller support having a strip-like part having one end thereof bent to form a hollow 45 head which conformably engages in the dove-tailed guide-way and has movement in the latter independent of the carrier movements and into and out of engagement with the notches.

50 In testimony whereof I affix my signature.

FRANK H. BLAISDELL.
